UNITED STATES PATENT OFFICE.

JOHN GITTLEN DEITZ, OF TULSA, OKLAHOMA.

DOOR CONSTRUCTION.

Application filed October 8, 1924. Serial No. 742,463.

To all whom it may concern:

Be it known that I, JOHN G. DEITZ, a citizen of the United States, and a resident of Tulsa, in the county of Tulsa and State of 5 Oklahoma, have invented certain new and useful Improvements in Door Constructions, of which the following is a specification.

My invention relates generally to door constructions of the type having a door 10 mounted to move laterally edgewise between open and closed positions, more particularly to a door construction for show cases, cabinets, and like structures, and it consists in the combinations, constructions and arrangements herein described and claimed.

An object of the present invention is to provide a door construction of the character described having a door urged continuously toward closed position.

20 A further object of the invention is the provision of a door construction of the character described having simple, reliable and efficient means adapted to act automatically on the moving door of the construction to 25 fully open position to releasably hold the door against moving toward closed position.

A still further object of the invention is the provision of a door construction of the 30 character described having a door mounted to move anti-frictionally at a substantially uniform speed toward closed position.

A still further object of the invention is the provision of yielding means for cushioning 35 the movement of the door immediately before the latter reaches fully closed position and for frictionally holding the door in fully closed position.

Other objects and advantages will be 40 apparent from the following description, considered in conjunction with the accompanying drawings, forming a part of this application, in which:

Figure 1 is a front view of a cabinet 45 structure equipped with a door construction embodying the invention, portions of the structural elements of the cabinet being broken away and other portions being shown in section.

50 Figure 2 is a fragmentary vertical section substantially along the line 2—2 of Figure 1,

Figure 3 is a view similar to Figure 2, taken substantially along the line 3—3 of Figure 1,

55 Figure 4 is a perspective view of the lower

or bottom frame member of the mounting for a door in the doorway construction exhibited in Figure 1,

Figure 5 is a view similar to Figure 1, showing a modified form of doorway construction,

Figure 6 is a section substantially on the line 6—6 of Figure 5, and

Figure 7 is a fragmentary perspective view of a carriage for movably supporting a 65 door of the construction exhibited in Figures 5 and 6.

As is well known, show cases and like cabinets for stores and like places ordinarily employ sliding doors arranged in pairs. 70 These doors move horizontally edgewise between open and closed positions and may be supported on rollers or like anti-friction members so that they can be moved easily between closed and opened positions. Such 75 doors are frequently left open, thus permitting entrance of dust, insects and the like. Also it sometimes is desirable that the doors shall be kept closed in order that the temperature of the interior thereof may be kept 80 higher or lower than the temperature of the space in which the cabinet or show case having the door is located. When the door is left open for any appreciable time, the temperature of the interior of the cabinet or 85 case having the door cannot be kept different from that of the surrounding space.

A door construction embodying the invention obviates the objectionable features 90 ordinarily encountered in door constructions now generally in use by providing a door and mounting therefor adapted to cooperate to cause the door to move automatically to closed position from any position other than fully open position.

95 In Figure 1, I show the front wall of a cabinet or other structure having two substantially rectangular openings located in side by side relation, each of the openings being defined by a horizontal upper frame member 1, a horizontal lower frame member 2, a vertical end member 3, and a second vertical frame member 4, the latter being common to the two openings. Also, the lower frame members 2 may be portions of 100 the same member of the cabinet or like structure as may both the upper frame members 1.

A pair of cooperative lateral edgewise doors 5 and 6 respectively is provided for 110

each of the openings just mentioned. Each door 5 or 6 has a width slightly greater than half the width of the opening in which it is disposed so that the doors 5 and 6 will overlap when the door 5 is in abutting relation at one side edge with the frame member 3, and the door 6 is in abutting relation at one side edge with the frame member 4.

The bottom frame member 2 is formed to provide a pair of oppositely inclined juxtaposed tracks 7 and 8 respectively, the inclination of each of these tracks from the horizontal being uniform from one end thereof to its opposite end and the same for both of the tracks. The track 7 extends for half its length as the bottom of a groove 9 in the upper side of the lower frame member 2 and the track 8 likewise extends for half its length as the bottom of a groove 10 in the upper face of the lower frame member 2. The tracks 7 and 8 both extend the full width of the opening which is partially defined by the lower frame member 2.

The top frame member 1 is provided with a channel 11 in its lower face which is located directly above the track 7 and with a channel 12 which is located directly above the track 8. The channels 11 and 12 extend the full width of the opening which is partially defined by the top member 1. The door 5 is adapted to move laterally edgewise with the upper edge portion thereof received in the channel 11 and with the lower edge portion thereof partially received in the groove 9, the door 5 being movably supported at its lower end upon the track 7. The door 6 is adapted to move laterally edgewise on the track 8 with the upper edge portion thereof received in the channel 12 and with the lower edge portion thereof partially received in the channel 10. The door 5 has the lower end wall thereof inclined as indicated at 13 to correspond to the inclination of the track 7. The door 6 has the lower end wall thereof inclined to correspond to the inclination of the track 8 indicated as at 14. The doors 5 and 6 may be anti-frictionally supported for movement on the supporting tracks in any suitable known manner. For example, each of the tracks may have a rail in the form of a rib 15 and extending longitudinally thereof intermediate the width of the track and each of the doors 5 and 6 may have a longitudinally extending groove 16 in the lower end wall thereof in which wheels 17 are rotatably supported at intervals along the length of the groove 16, each of the wheels 17 having a peripheral groove as at 18 for engaging with the crown portion of the rail 15, with which the wheels 16 have rolling contact.

The vertical distance between the highest point on each of the tracks 7 or 8 and the upper wall of the channel 11 or 12 which is

located directly thereabove, is slightly greater than the height of each of the doors so that each door will extend at its upper end nearly to the top wall of the channel 11 or 12 in which it is disposed when the door is supported on the higher half portion of its supporting track, or in other words, in open position. When each door is supported on the lower half portion of its supporting track, the door will extend into the channel 11 or 12 which is located directly thereabove, but of course will be located at its upper end a considerable distance above the top wall of the channel 11 or 12 with which it is associated.

The doors 5 and 6 are provided adjacent to their remote side edges with handles, as at 19 which can be grasped and manipulated conveniently to effect movement of the doors from closed to open position. Each of the rails 15 is formed with a depression 20 in the crown portion thereof adjacent to the higher end of the track. When either of the doors 5 or 6 has been moved up the inclined track upon which it is supported to fully open position, one of the wheels 18 upon which that door is rollingly supported will engage with the depression 20 to releasably hold the door against returning to closed position under the influence of gravity. However, as soon as the door has been moved slightly toward closed position, the wheel 18 which has been engaged with the depression 20 will roll out of the depression 20 and the door will move by gravity down the inclined track upon which it is supported to fully closed position. A bumper 21 which is made of rubber or like material is secured at the lower end of each of the tracks 7 or 8 on the end member 3 or 4 in position to be engaged by a door 5 or 6 at the time the latter moves to fully closed position, thus obviating any jar or shock which might cause injury to the door. The door is releasably held in fully closed position by a spring finger 22 which has the form best seen in Figure 1, and is secured at one end within a channel 11 or 12 to the upper wall of the channel, as at 22, so that the free end of the spring finger presses downwardly on the upper end wall of the door with which it is associated when that door has been moved to fully closed position, thus not only aiding one of the bumpers 21 in cushioning the movement of the door when it reaches fully closed position, but also serving as a friction latch to hold the door against grappling or accidental displacement from fully closed position.

From the foregoing description of the various parts of the device the operation thereof may be readily understood. The doors 5 and 6 will closely overlap each other at their adjacent side edges when both the doors are in fully closed position. Each of

the doors will move to closed position automatically unless the door has been moved to fully open position, in which event the engagement of one of the wheels 18 with the 5 depression 20 on the rail of the supporting track will hold the door in fully open position until it has been moved manually a short distance from fully open position.

The inclination of the lower end walls of 10 the doors assures close contact of such doors throughout their width with the supporting tracks so that no openings are left between the tracks and the lower ends of the doors, irrespective of the positions of the doors on 15 the tracks. A cross bar or rail 23 at the lower end of the cabinet extends between the vertical members 3 and 4 on the front face of the lower frame member 2 and conceals the tracks 7 and 8.

20 In the modification shown in Figure 5, a doorway is defined in a cabinet or like structure by a top frame member 25, a bottom frame member 26, and a pair of end frame members 27. The bottom frame member 26 is formed to provide a pair of oppositely inclined juxtaposed tracks 28 and 29, respectively, which are identical in essential respects with the tracks 7 and 8 which have been hereinbefore described. The top frame member 25 is formed with a channel 30 in its lower face which is located directly above the track 28, and with a channel 31 which is located above the track 29. Doors 32 and 33 respectively are adapted to move laterally 35 edgewise in the doorway of the modification to control the latter. The door 32 has the lower end wall thereof inclined to correspond to the inclination of the track 28, and is of sufficient height to extend at its upper end into the channel 30 when it is rollingly supported at its lower end upon the track 28 in a manner which will be presently described. Likewise the door 33 is of sufficient height to extend at its upper 40 end into the channel 31 when it is rollingly supported at its lower end upon the track 29. Each of the doors 32 and 33 is formed of plate glass and has the lower edge portion thereof provided with a wear resisting facing or shoe 34 of metal or other suitable material. A carriage is interposed between the facing 34 of each of the doors 32 or 33 and the track with which that door is associated for rollingly supporting the door 45 for edgewise lateral movement. Such carriage may comprise a frame having a pair of parallel frame members 35 connected at their ends, as at 36 and having alined openings at intervals along their length in which the axles or trunnions of rollers 37 are journaled, the rollers extending both above and below the frame members 35. The carriages are adapted to move on the tracks and since 50 each of the tracks has a half portion thereof formed as the bottom of a groove in the

upper side of the lower frame member 26, the side walls of that groove will serve as stops for preventing displacement of the carriage which is partly disposed in that groove from the longitudinal median portion of the track on which the carriage is supported.

Each of the end members 27 carries a bumper 38 which may be made of felt or like material, and is located at the lower end 55 of one of the tracks 28 or 29 for engaging with the door which is supported on that track when the door is in fully closed position. Each door may be releasably held in fully open position by a spring latching member 39 which comprises a strip of spring material attached at one end to the upper wall of a channel 30 or 31, as at 40, and has the free end portion thereof bent into a half loop as indicated at 41 for engaging 60 with a depression 42 in the upper wall of the associated door when the latter is in fully open position. The loop portion 41 or the spring latching member is located directly beneath a depression 43 in the upper wall of the channel 30 or 31 in which the spring latching member is disposed so that when the door is actuated manually 65 in such manner as to urge it from fully open position, the loop portion 41 of the spring latching member will move upwardly 70 into the recess 43 and will then disengage the depression 42, thus releasing the door so that it will move by gravity to fully closed 75 position.

Obviously, the invention is susceptible of embodiment in forms other than those which have been illustrated in the accompanying drawings, and I therefore consider as my own all such modifications and adaptations 80 thereof which fairly fall within the scope of the appended claims.

I claim:

1. In a door construction, a frame defining an opening and comprising a horizontal top member and a stationary bottom member having an inclined track at the upper side thereof, said top member having a channel formed in its lower side directly above said track, and a door slidable on said stationary inclined track to and from position to close said opening, the lower edge of the door being inclined to correspond to the inclination of the track, the upper edge of the door being horizontal, and the upper edge portion of the door extending into the channel in said top frame member.

2. In a door construction, a frame defining an opening and comprising a horizontal top member and a stationary bottom member having an inclined track at the upper side thereof, said top member having a channel formed in its lower side directly above said track, a door adapted to move edgewise on said track to and from position to close said

opening, the lower edge of the door being inclined to correspond with the inclination of the track, the upper edge of the door being horizontal and the upper edge portion of the door extending into the channel in said top frame member, and anti-friction means at the lower edge of the door movably supporting the door on the track.

3. In a door construction, a frame defining an opening and comprising a horizontal top member and a stationary bottom member having an inclined track at the upper side thereof, said top member having a channel formed in its lower side directly above said track, and a door slidable on said stationary inclined track to and from position to close said opening, the lower edge of the door being inclined to correspond to the inclination of the track, the upper edge of the door being horizontal, the upper edge portion of the door extending into the channel in said top frame member, and guide means carried by said frame and engaging with the upper end portion of the door to prevent displacement of the door from said track.

4. In a door construction, a frame defining an opening and comprising a horizontal top member and a stationary bottom member having an inclined track at the upper side thereof, said top member having a channel formed in its lower side directly above said track, and a door slidable on said stationary inclined track to and from position to close said opening, the lower edge of the door being inclined to correspond to the inclination of the track, the upper edge of the door being horizontal, the upper edge portion of the door extending into the channel in said top frame member, cooperative members carried by said frame and said door for releasably holding the door in fully open position.

5. In a door construction for a show case, cabinet or like structure, a frame comprising a horizontal upper frame member, a horizontal lower frame member and a pair of spaced vertical frame members extending between said horizontal frame members and cooperating with the latter to define an opening, said lower frame member being formed to provide a pair of juxtaposed oppositely inclined tracks on its upper side, each extending the full width of the opening, said upper frame member being formed to provide a pair of juxtaposed channels in its lower side, one located directly above one of said tracks and the other located directly above the other track, and a pair of cooperative edgewise laterally movable doors for controlling said opening, one of said doors being movably supported on one of said tracks and the other door being movably supported on the other track, each of said doors extending into the channel above the track on which the door is supported and at least one of the doors having a width greater than half the width of the opening, each of said doors being inclined at its lower end to correspond to the inclination of the track on which it is supported.

the doors having a width greater than half the width of the opening.

6. In a door construction for a show case, cabinet or like structure, a frame comprising a horizontal upper frame member, a horizontal lower frame member and a pair of spaced vertical frame members extending between said horizontal frame members and cooperating with the latter to define an opening, said lower frame member being formed to provide a pair of juxtaposed oppositely inclined tracks on its upper side, each extending the full width of the opening, said upper frame member being formed to provide a pair of juxtaposed channels in its lower side, one located directly above one of said tracks and the other located directly above the other track, and a pair of cooperative edgewise laterally movable doors for controlling said opening, each of said tracks having the lower half portion thereof formed as the bottom of a channel in the upper face of the lower frame member, a rail on each of said tracks, each of said rails having a depression in the crown portion thereof adjacent to the highest point on the rail, and wheels supporting said doors on said rails so that the doors extend at their upper ends into the channels in the upper frame member, one of the supporting wheels of each door being adapted to engage with the depression in the supporting rail when the door is in fully open position to releasably hold the door against return movement toward closed position.

7. In a door construction for a show case, cabinet or like structure, a frame comprising a horizontal upper frame member, a horizontal vertical frame member and a pair of spaced vertical frame members extending between said horizontal frame members and cooperating with the latter to define an opening, said lower frame member being formed to provide a pair of juxtaposed oppositely inclined tracks on its upper side, each extending the full width of the opening, said upper frame member being formed to provide a pair of juxtaposed channels in its lower side, one located directly above one of said tracks and the other located directly above the other track, and a pair of cooperative edgewise laterally movable doors for controlling said opening, one of said doors being movably supported on one of said tracks and the other door being movably supported on the other track, each of said doors extending into the channel above the track on which the door is supported and at least one of the doors having a width greater than half the width of the opening, each of said doors being inclined at its lower end to correspond to the inclination of the track on which it is supported.
